UNITED STATES PATENT OFFICE

GEORGE E. DENMAN, OF OAKLAND, CALIFORNIA

GAS LIFT PUMP

Application filed January 30, 1929, Serial No. 336,098. Renewed November 13, 1931.

This invention relates to improvements in gas or air lift pumps, and its objects are to provide a simple and efficient pump, capable of pumping oil, gas, or water out of deep 5 wells by means of compressed air or gas; the pump set forth herein being an improvement on the device shown in United States Patent No. 1,322,483, issued to me on the 18th day of November, 1919.

10 Another object of this invention is to provide a pump with a joint seat therein, whereby the entire pump mechanism may be pulled out of the well without disturbing the outer casing, for repairing or replacing parts and 15 valves.

Another object is to provide in the pump pipe line, one or more booster valves whereby the deep well pumps may be operated with a lower pressure than would be required if 20 no booster valves be used.

While the drawing illustrates an embodiment of the invention, it is to be understood that in adapting the same to meet different requirements, various changes in the form, 25 proportions and minor details of construction may be resorted to without departing from the nature of the invention or sacrificing any of its advantages.

The principle exemplified in this improved 30 pumping mechanism is that of applying an accelerating lifting force at points intermediate the intake and discharge ports, and between the initial application of force and the final discharge nozzle whereby minimum air 35 pressure, or gas pressure, will lift a maximum quantity of oil, gas, water, or liquid that is to be pumped.

In the drawing: Figure 1 is a vertical sectional view of my improved pumping mechanism. Fig. 2 is an enlarged and fragmentary 40 sectional view showing a modified form of certain of the operative parts.

Referring to the drawing in detail, the well casing 3 extends below the water or air level, 45 and has at the bottom, a perforated tubing 4, and is representative of any deep well casing.

For maximum lifting capacity with minimum air lift, or gas lift pressure, my improved pumping mechanism consists of an 50 outer casing 5, a union member 6, a reducing

coupling 7, a conduit tubing 8 which extends upwardly, and a supporting cap 9, through which discharge tubing 8 extends, secured to the top of the well casing. Outer casing 5 is provided at the bottom with a check valve 55 10, serving to control the flow of water, gas, or oil, into the casing. At the top of casing 5, there is provided a bushing chamber 11, having apertures 12, which serve to admit air or gas pressure from chamber 13, formed by upper conduit tubing 8, into chamber 14, formed by outer casing 5. An inner and concentric casing 15, extends from bushing member 11, downwardly, and terminates adjacent to valve 10, and has, at the bottom, a 60 similar check-valve 16. Casing 15 has, adjacent to bushing member 11, a concentric pressure nozzle 17 arranged to admit gas or air pressure from chamber 14, into the inner casing. Bushing member 11 is made with a 65 tapering joint connection with a supporting sleeve 18, fixed to outlet conduit 19, extending upwardly and through a closure cap 20, on the upper extremity of conduit tubing 8.

The initial lifting pressure is admitted 70 through nozzle 17 to outlet conduit 19, and is admitted to upper chamber 13 through pressure intake pipe 21, which is connected to a suitable pump 22. To accelerate the flow through outlet conduit 19, there is provided, 75 at one or more intermediate points, the booster valve 23, which consists of a sleeve member 24, having therein the apertures 25, to admit the pressure into conduit 19 beneath a check-valve 26, which has a ball valve member 27, retained within sleeve member 24, by a pin 28.

In the modified form in Fig. 2, the supporting sleeve 18 is slightly smaller in diameter than the inner diameter of conduit tubing 8, thereby allowing the outlet conduit 19, together with the booster valves that may be interposed therein, and inner pump casing 15, which has screw connection with sleeve 18, together with nozzle 17, and check-valve 16, to be withdrawn without disturbing the outer pump casing.

It may be seen that apertures 30 are provided in supporting sleeve 18. These apertures are normally closed by plugs 34. The 100

nozzle 17 is shown as provided with a closing plug 29, but is normally open. The apertures 32 are normally closed by plugs 33. Apertures 12, in bushing member 11, are shown as closed by members 31, but are normally in open position. If deemed necessary for any particular purpose, the closure members 31 may be placed in position, and the plugs 34 removed from apertures 30, 10 causing the pressure in the outer chamber to be admitted at this point.

Assuming the device is to be used in the ordinary manner, the apertures 30 and 32 are normally closed, and the nozzle 17 and apertures 12 are normally open. The pump then operates as follows: The check-valves 10 and 16 are located below the water or oil level, as the case may be. Air or gas pressure is then pumped into chamber 18, and passes 15 through apertures 12 into chamber 14. The fluid medium that is to be lifted, is forced by the pressure to pass through valve 16, and is then entrained by the flow of air or gas through nozzle 17, and is forced upwardly 20 through the outlet conduit 19. In accordance with the depth of the well, there will be one or more of the booster valves 23, which admit the air or gas to flow through apertures 25, and into conduit 19, thereby accelerating the 25 flow of the fluid medium passing upwardly therethrough. The check-valves provided prevent the oil or water from dropping back immediately when the air pressure is exhausted, and therefore it is not necessary to again 30 lift the same on resuming operation of the pump.

The air or gas pump set forth herein embodies the advantages of the accessibility of all working parts without disturbing the outer casing, and the interposition of accelerating and boosting means at successive points along the outlet conduit whereby a lower working pressure is required for the apparatus. By inserting certain of the plugs in 45 certain apertures, and by removing others from other apertures, the apparatus may be adapted for various purposes.

What is claimed is:

1. In an air or gas lift displacement pump, 50 the combination with an outer casing adapted to extend from top to the bottom of a well and to enclose a pressure chamber, a closure cap at the top of the outer casing, and a check-valve at the bottom of the outer casing, of a removable inner outlet conduit extending within the outer casing, a check-valve at the lower extremity of the inner outlet conduit and adjacent to the first-named check-valve 55 within the outer casing, a pressure nozzle within and concentric with the lower portion of the inner outlet conduit, means for admitting air or gas pressure to the chamber formed by the outer casing and inner conduit, and booster valves disposed along the inner

outlet conduit for admitting a boosting pressure therein.

2. In an air or gas lift displacement pump, the combination with an outer casing adapted to extend within an oil, gas, or water well, and beneath the level of the fluid medium therein, of a closure cap disposed at the top of the outer casing, a check-valve disposed at the bottom of the outer casing, a removable inner outlet conduit extending within the outer casing and concentrically therein, a check-valve at the bottom of the inner outlet conduit and adjacent to the first-named check-valve, means for admitting air or gas pressure to the chamber formed by the outer casing and inner conduit, and means for admitting the air or gas pressure from said chamber into the inner conduit at intervals along the length thereof, and a nozzle adjacent to the bottom of the inner conduit for admitting the air or gas pressure therein. 70

3. In an air or gas lift displacement pump, the combination with an outer casing adapted to extend within a well and beneath the level of the fluid medium therein, of a closure cap on the upper extremity of the outer casing, a check-valve disposed at the bottom of the outer casing to control the flow of fluid medium therein, a removable inner conduit extending concentrically within the outer casing and forming an annular chamber therewith, means for admitting air or gas pressure within the annular chamber, a check-valve at the bottom of the inner conduit, a pressure nozzle within and adjacent to the bottom of the inner conduit and in communication with the annular chamber, and other check-valves disposed along the length of the inner conduit and arranged for admitting the pressure therein. 90

4. In an air or gas lift displacement pump, the combination with an outer casing adapted to extend within an oil, gas or water well, and beneath the level of the fluid medium therein, of a closure cap disposed at the top of the outer casing, a check-valve disposed at the bottom of the outer casing, a removable inner outlet conduit extending within the outer casing, a check-valve at the bottom of the inner outlet conduit and adjacent to the first-named check-valve, means for admitting the air pressure or gas pressure to the chamber formed by the outer casing and inner outlet conduit, an initial nozzle for admitting the pressure within said chamber into the inner outlet conduit adjacent to the bottom thereof, and means for admitting the air or gas pressure from said chamber into the inner conduit along the length thereof without putting pressure on the well casing or adjacent soil formation. 100

Signed this 24 day of December, 1928.
GEORGE E. DENMAN.
